UNITED STATES PATENT OFFICE.

JOSEPH SALTZMAN AND WILLIAM C. VEITZ, OF CHICAGO, ILLINOIS; SAID VEITZ
ASSIGNOR TO SAID SALTZMAN.

PRESSING MACHINE.

Application filed April 22, 1920. Serial No. 375,730.

To all whom it may concern:

Be it known that we, JOSEPH SALTZMAN and WILLIAM C. VEITZ, citizens of the United States, residing at Chicago, in the 5 county of Cook and State of Illinois, have invented certain new and useful Improvements in Pressing Machines, of which the following is a specification.

Our invention has reference more particularly to a machine wherein a pressing iron 10 is mounted for elevational adjustment to and from an ironing board or pressing buck and adapted to be manually operated over the top of the buck to press clothes or other articles on the buck.

Pressing irons, such as are commonly used in tailoring or clothes pressing establishments are quite heavy and it is desirable to employ a support therefor to facilitate lifting the iron and hold same above the pressing buck and at the same time permit the iron to be manipulated on the buck during the pressing operation with substantially the same freedom as if it were not connected 25 with the supporting means.

The principal objects of our invention are to provide an improved pressing machine of simple form, which is convenient to operate and wherein the iron is suspended in such 30 a manner as to afford the greatest ease of manipulation during the pressing operation; to carry the support for the iron directly on an elevating spring so as to simplify the construction and facilitate the operation of the 35 machine; to provide an improved means for regulating the elevation of the carrier arm and pressing iron; to provide an enclosed adjustable mechanism for varying the length of the carrier arm; to provide an improved 40 pressing buck for a machine of this character; and in general to provide an improved pressing machine which is economical to manufacture and possesses advantages which have not heretofore been provided in machines of this character.

On the drawings, Fig. 1 is a side view of the pressing machine; Fig. 2 a view looking at the front thereof; Fig. 3 an enlarged view of the carrier arm, partly in section 50 on the line 3—3 of Fig. 2; Fig. 4 an enlarged, sectional view on the line 4—4 of Fig. 1; Fig. 5 a fragmentary view, partly in section of the spring bearing; and Fig. 6 a top view of the pressing buck.

The supporting frame of this machine

comprises a pair of spaced standards 1, constructed in a unitary form or otherwise as desired, and having a top 2 mounted thereon. At the rear of the standards 1 and near the bottom thereof is a cross bar 3 having a bearing 4 for the vertical shaft 5 which extends up through the top 2 and is journaled in a bearing ring 6 oscillatably mounted between upright lugs 7, each of which has a cap screw 8 inserted therethrough and engaging in the ring 6 at diametrically opposite points. A frame 9 composing a part of the adjustable carrier arm for the iron has a hub portion 10 at one end telescoped on to the upper end of the shaft 5 and held 65 from turning thereon by a pin 11, the ends of which engage in slots 12 at opposite sides of the hub 10 so as to permit vertical adjustment of the hub on the shaft 5. A collar 13 is secured on the shaft 5 a short distance 70 below the hub 10 by a pin 14, and an adjusting screw 15 is threaded through the hub 10 parallel with the shaft 5 and engages against the top of the collar 13 so as to facilitate vertical adjustment of the frame 9 75 on the shaft 5. A set screw 16 is threaded into the hub 10 to lock the frame member 9 on the shaft 5 in the adjusted position.

The frame 9 projects horizontally from the shaft 5 and has an opening 17 extending lengthwise therethrough to accommodate the bar 18, and at the outer end of the frame 9 and extending below the bar 18 are spaced ears 19, between which a friction roller 20 is pivoted on a bolt 21 which is passed 80 through the ears 19. At the inner end of the frame 9 there is a similar pair of ears 22 extending above the bar 18 with a friction roller 23 pivoted therebetween on the bolt 24 so as to engage the upper edge of the bar, and these rollers 20 and 23 afford an anti-friction support enabling the bar 18 to be easily adjusted lengthwise through the frame 9.

Secured to the outer end of the bar 18 by rivets 25 or in any other desired manner is an extension 26 having a bore 27 in alignment with the bar 18. A pin 28 is inserted in the bore 27 and has an annular groove 29 at the inner end loosely engaged by a screw 30 to retain the pin in the bore 27 and permit pivotal movement thereof. This pin 25 has a ball 31 at the outer end to which a pressing iron is attached, said iron comprising the base 32 and handle 33 which are se- 105 110

cured together by the bolt 34. The base 32 has boss 35 on the top with a concave recess in the upper face conforming to and engaging the surface of the ball 31, and the handle 33 of the iron has a depending boss 36 likewise conforming to and engaging the ball. The ball 31 has an opening 37 therethrough somewhat larger than the bolt 34, which latter is secured to the base 32 and projects 10 up through the boss 35 and the aperture 37 of the ball and is threaded into an opening 38 in the boss 36 of the handle. The handle 33 is turned on the bolt 34 so as to loosely engage the ball 31 between the lugs or half 15 bearings 35 and 36 and permit the iron to swivel on the ball 31, the parts being locked in such engagement by the lock nut 39 which is threaded in the end of the bolt 34 against the lug 36 of the handle. Thus the pressing 20 iron is not only adapted to tilt forwardly and rearwardly by reason of the pivotal connection of the supporting pin 28 in the bar extension 26, but also has a limited universal movement on the ball 31, enabling the iron 25 to be manipulated in any manner which may be required in the operation of pressing.

A guard 40 consisting of an inverted trough shaped sheet metal cover is placed over the bar 18 and frame 9, and has a cap 30 41 at one end secured by the pin 42 or in other convenient manner to the inner end of the bar 18, and a cap 43 at the other end secured on the bar extension 26 in any satisfactory manner.

35 A pressing buck 44 is mounted at the front of the table 2 to support the article of clothing or other material which is to be pressed and in the operation or use of the pressing machine, the iron 32-33 which is normally held at a slight elevation above the pressing buck 44, is depressed so as to bear upon the pressing buck. For the purpose of sustaining the iron and supporting arm 9-18 in the elevated position and permitting same 40 to be depressed when required, I provide a bearing collar 45 on the shaft 5 at a distance below the top 2 and hold the collar against axial movement on the shaft 5 by a pin 46 passed through the shaft just above 45 and engaged by the collar. The collar has a ball race in its under face engaged by bearing balls 47, which balls also engage in a ball race in the upper face of a bearing ring 48 loosely encircling the shaft 5 directly below the collar 45. The ring 48 is provided at diametrically opposite sides with loops or eyes 49 or other suitable fastening means to which the lower ends of supporting springs 50 are attached, these springs being secured 50 at the upper end respectively to the side frames 1 in any suitable manner, as for example, by hooked extremities 51 engaging in apertures 52 of flanges of the side frames.

60 A pedal bar 53 is pivoted at its end on a pivot pin 54 between the lugs 55 at the rear

of the supporting frame and extends out beyond the front of the frame as shown in Fig. 1, terminating in a pedal 56 which is conveniently accessible to the operator when standing in working position at the front of the machine. The forward end of the pedal bar is embraced between a pair of spaced bars 57 which guide the pedal bar, said bars 57 being supported at their upper and lower ends by bolts 58 extending between the side frames 1 and provided with spacing sleeves 59 for holding the bars in an intermediate position between the frames 1. The proper separation of the bars 57 to accommodate the pedal bar 53 there between may be effected in any convenient manner, as by interposing a short sleeve similar to the sleeves 59 on each bolt 58 between the ends of the bars 57.

65 A bumper 60 is held between the bars 55 at their upper ends to bear the impact of the pedal when it is elevated by the lifting tension of the springs 50. This bumper may be clamped between the bars or may be perforated to take the bolt 58 and serve as a 90 separator for the bars 57, if desired. The pedal bar 53, adjacent its rear end extends between the bifurcated extremities 61 of a connector 62 and bears against an insert 63, 95 which is pivoted between the bifurcated ends 61 on the pin 64, the upper surface of the insert being rounded as shown to permit a rocking engagement. The upper end of the connector 62 is of a looped formation with a top cross part 65 having an aperture in 100 which the lower end of the shaft 5 is pivotally secured. The lower end of the shaft is preferably of reduced diameter to afford a shoulder engaging against the top of the cross part 65, and there is a cap screw 66 105 threaded into the lower end of the shaft 5 against the washer 67, which bears against the end of the shaft and loosely engages under the cross piece 65 to pivotally connect the connector 62 to the lower end of the 110 shaft.

115 The pressing buck which has hereinbefore been referred to by the reference numeral 44 is of metal and comprises an elongated plate extending transversely of the machine at the front thereof and provided with legs 68 intermediate of its ends which are secured to the top 2 by bolts 69, and hold the pressing buck or top plate thereof at an elevation above the machine top 2. The top 120 plate of the buck has enlarged rounded ends with a reduced intermediate portion as shown in Fig. 6 so that fitted coats or articles of such character may be laid smoothly on the top plate and said plate is skirted by 125 a depending flange 70 which serves to reinforce the top plate and protect the garments thereon from a gas burner which is placed under the plate. This burner consists of a pipe 71 extending lengthwise of 130

the buck, midway of its width and closed by end caps 72 which are secured to lugs 73 depending from the top plate of the buck so as to support the pipe at a short distance 5 therebelow. A gas supply pipe 74 communicates with the pipe 71 intermediate of its ends as shown in Fig. 2 and the upper surface of the pipe 71 is provided with a plurality of perforations 75 so that the pipe 71 10 serves as a gas burner for heating the top plate of the pressing buck.

In the operation of the machine the gas burner 71 is lighted and controlled so as to heat the top plate of the pressing buck as 15 required and the iron 32 depressed by pressure on the pedal 56 so that the iron may be operated on the garment or other article placed on the pressing buck. The pivotal connection of the iron with the bar 18 20 through the ball support 31 and pivot 28 and the sliding connection of the bar 18 with the frame 9 and the pivotal mounting of the shaft 5 enables the operator to manipulate the iron by means of the handle 33 25 over the garment without interference or inconvenience due to the support of the pressing iron.

The mounting of the upper end of the shaft 5 in the swivel bearing 6 avoids binding or cramping of the shaft in the bearing 30 due to the laterally disposed weight on the upper extremity of the shaft and the direct connection of the springs 50 through the ball bearing connection 45-48 with the 35 shaft 5 permits the shaft to swing with ease and respond readily to the elevating position of the springs 50 when pressure on the pedal 56 is released.

The adjustment of the frame 9 on the 40 upper end of the shaft 5 which is effected by the adjusting screw 15 permits the desired elevation of the arm in the operative position to be attained and also the desired co-operating relation between the pedal 56 and 45 supporting arm so that the iron engages the garment on the pressing buck when the pedal is depressed to the desired extent.

While we have shown and described our

invention in a particular form it is to be understood that various changes and modifications may be made without departing from the principles of our invention, the scope of which is to be determined by the appended claims.

We claim as our invention:

1. In a pressing machine, the combination of a frame having a pair of vertically spaced bearings, an upright shaft journaled in the bearings and slidable axially therein, a pair of springs positioned at opposite sides of the shaft and having their upper ends connected with the frame, a bearing ring rotatable on the shaft and connected to the lower ends of the springs, an arm extending laterally from the shaft and having a pressing iron on the outer end thereof and means controlled by the operator for sliding the shaft downwardly in its bearings against the tension of the springs.

2. In a pressing machine, the combination of a frame having a pair of vertically spaced bearings, one of which is horizontally pivoted on the frame, a shaft mounted to rotate in the bearings and having an arm extending laterally therefrom with the pressing iron on the outer end thereof, means for resiliently holding the shaft in an elevated position and operator controlled means for sliding the shaft axially in the 75 bearings against the tension of the resilient 80 means.

3. In a pressing machine, the combination of a frame having an upright shaft journaled in the frame and provided with a longitudinally extensible arm with a pressing iron on the outer end, spaced bearings on the frame for supporting the shaft so as to oscillate and slide therein, a ring on the shaft and having a ball bearing connection therewith so as to rotate on the shaft, and a spring hanger suspended from the frame and connected with the ring for resiliently holding the shaft in an elevated position.

Chicago, Ill., April 7, 1920.

JOSEPH SALTZMAN.

WILLIAM C. VEITZ.
